SPRAY MACHINE

Lloyd E. Pitner, Milwaukee, Wis.

Application October 18, 1937, Serial No. 169,580

18 Claims. (Cl. 299—41)

My invention relates to spray machines and more particularly to those machines adapted to distribute liquid insecticides.

One of the primary objects of my invention is 5 to provide a spray machine including an improved compact, mobile unit adapted to be conveniently transported from place to place whereby it may be used to spray pest infected fields throughout a large territory.

10 During its use in the field the spray machine utilizes a spray rig arrangement including spray booms, these booms, for economy, being long, thereby permitting a maximum area to be sprayed per unit of movement of the machine. 15 However, due to their great length, these booms are cumbersome and not well adapted to withstand ordinary road travel from place to place when in their extended, spraying position. Consequently, in order to adapt my spray machine to 20 road travel and to eliminate strain and injury to the spray rig mechanism during road travel, and as another object of my invention, I have provided an improved boom and boom supporting arrangement which is adapted to be folded 25 into a compact unit, suitable for road travel with a minimum of effort and without complicated folding operations on the part of the operator. Furthermore, the essential control of the unit 30 may be had from a single operator's station.

Still another object of the invention is to provide an improved device of the above class in 35 which both the spray rig and booms are freely and independently movable to be adapted to the contour of the land being sprayed, this movement of the rig and booms also being brought about by a minimum of effort on the part of the operator and also being controlled by an extremely simple operating mechanism located at the single operator station.

40 Another object of my invention is to insure uniformity of distribution of the spray solution by providing a truck speed indicator, a spray circuit pressure indicator and a spray circuit control valve all together at an operator's station whereby the operator can control the spray feed in accordance with changes in truck speed, to maintain the amount of insecticide fed constant per unit of area of the field.

50 Still another object of the invention is to provide a spray liquid pressure circuit arrangement wherein the pressure in said circuit may be utilized for adjusting the position of the booms, the position of the rig and for folding the booms. 55 Other objects and advantages of my inven-

tion will be apparent from the following description and accompanying drawings, in which:

Fig. 1 is a diagrammatic side elevation of the spray mechanism mounted upon a truck with the booms folded in readiness for road travel; 5

Fig. 2 is a diagrammatic rear elevation of the spray mechanism mounted on the truck with the booms unfolded to a position in readiness for the spraying operation;

Fig. 2A is a fragmentary view of the hydraulic 10 controls for lifting the booms;

Fig. 3 is a rear view of the spray rig proper, showing the manner in which the control for the spray liquid circuit is mounted thereon and connected therewith;

Fig. 4 is a view taken on line 4—4 of Fig. 3;

Fig. 5 is a plan view of the spray rig proper with the booms in unfolded position;

Fig. 6 is a view taken on the line 6—6 of Fig. 4; and

Fig. 7 is a perspective view of the liquid pumping apparatus showing the liquid circuits connected thereto.

It is understood that the embodiment disclosed herein is a preferred form and is for illustrative purposes only, being adaptable to change without departing from the spirit and scope of the invention set out in the appended claims.

Referring to the drawings, particularly Fig. 1, the entire spray assembly is shown mounted on 30 the rear platform of a truck and comprises generally a boom supporting and carrying assembly A (hereinafter referred to as the spray rig), a liquid pressure system B (shown in detail in Fig. 7), a liquid supply tank C, and a circuit control 35 unit D (shown in detail in Fig. 6). Conduits, hereinafter to be described in detail, conduct liquid from the supply tank to the pressure system and other conduits lead from the latter system back to the tank, this combination of circuits comprising the circulating and agitating system. Conduits are also provided to conduct liquid under high pressure from the pressure system to the control unit and thence through the boom outlets to the atmosphere. These circuits 40 constitute the liquid delivery system.

In order to attain compactness by folding whereby my spray rig may be adapted for road travel, I provide generally a pivotable boom supporting structure into which the booms which 50 extend beyond the confines of the supporting structure may be folded, while the entire supporting structure itself may then be folded forwardly upon a truck or carriage upon which the rig is mounted. In order to provide vertical adjust- 55

ment for the booms to regulate the height thereof with respect to the tops of the plants being sprayed, I provide a supporting structure which is vertically adjustable with respect to the truck or carriage upon which it is mounted. In the present embodiment the supporting structure for the booms comprises a lower horizontally positioned set of struts 10, a pair of upright struts 11 each having its lower end secured to the forward end of the adjacent strut 10 (the forward strut 10 being located directly beneath a cross bar 12 in Fig. 5). The upper cross bar 12 to which the upper ends of the upright struts 11 are connected has secured thereto the upper ends of lean-to struts 13, the lower ends of which are secured to the rearmost laterally extending strut 10.

The spray boom is shown herein as comprising three sections, a central section 14 and a pair of laterally extending side sections 15, each having suitable spray nozzles 14a and 15a therein respectively. The section 14 extends between and is secured to substantially the center point of each of the longitudinal struts 10 while the side sections 15 are secured by swivel joints 16 to substantially the same point of said struts 10. By virtue of these swivel joints, free, independent movement of the boom sections 15, presently to be described, may be had, to maintain them parallel to the ground adjacently below, throughout the travel of the vehicle over undulated land.

This boom supporting structure comprising struts 10 and 11, crossbar 12, and struts 13, is movable vertically to regulate the height of the booms in accordance with the height of the plants being sprayed, and, as shown in the present embodiment, the struts 11 extend through suitable slideways 11a in which the struts 11 are vertically movable. These slideways are mounted on the upright elements of a rectangular frame comprising upright elements 11b and transverse elements 11c, this frame being in turn pivotally mounted on the upright standards 17 which are rigidly secured to the rear end of the truck platform. Thus it will be seen that adjustment of the vertical position of struts 11 in slideways 11a will cause like vertical adjustment of the position of struts 10 and cross bar 12 along with the appended booms 14 and 15.

The booms 15 are supported against excessive horizontal movement in such a manner that they are held substantially non-rigidly in the positions shown in Figs. 2 and 5. Being so supported, they are not subject to breakage and undue strains if, by accident, they should strike a fence post or the like and be shifted horizontally rearward about universal joints 16. To provide such a support, there are embodied herein elevating cables 22, the operation of which will be described in detail presently. These cables extend from the upper part of the spray rig downwardly to the about center of the booms 15. Suitable fasteners 18 are mounted on the booms 15 and have the lower ends of cables 22 secured thereto. It will be readily understood that these cables 22 regulate the horizontal position of booms 15. Reference to Fig. 5 will show that the cables 22 are at an angle with respect to the longitudinal struts 10 and in order that the booms 15 do not gravitate forwardly and downwardly when in the position shown in Figs. 4 and 5, there is provided guy wires 19 which have one end secured to the rear end of the adjacent strut 10 and the other secured to the adjacent fasteners 18. From the above it will be seen that

should the boom 15 strike some stationary object as the vehicle moves forwardly they will move about the joint in an arc rearwardly and upwardly until the object has been passed.

As above described, the boom supporting structure is mounted on the truck by uprights 17 in such a manner that it may be pivoted forward in a body to form a compact unit suitable for road travel. In the present embodiment this is accomplished by pivoting the rectangular frame 11b-11c, the boom supporting structure and the booms on uprights 17 at the end of the truck platform about suitable securing pins 16b into a position shown in Fig. 1. The spray rig may then be secured in this position by suitable anchor 15 wires, one of which is shown at 16c.

To the end that the booms 15 may be raised and lowered in accordance with changes in the contour of the land and also that they may be folded for road travel, I provide the cables 22, 20 the outer ends of which are anchored at the approximate centers of booms 15. Each of these wires 22 extends upwardly and over one of the pulleys 23 mounted on each end of cross piece 12 beneath a guard 23a, inwardly along said cross piece to about the center thereof, and down and around one of the pulleys 24 rotatably positioned beneath the guards 25. The ends of wires 22 adjacent pulleys 24 are suitably anchored to the cross piece as at 26.

Each of the pulleys 24 is rotatably mounted on the end of a piston rod 27 adapted to be shifted longitudinally of the cross piece 12 by pressure exerted within each of the cylinders 28 in which the rods 27 and their respective pistons are adapted to reciprocate. Thus it will be seen that with such a construction any increase of pressure within one or both of the cylinders 28 will cause outward movement of one or both of the pulleys 24 with respect to its cylinder, thereby taking up the length of one or both of the wires 22 over pulleys 23 to raise one or both of the booms 15 (see Fig. 2A). On the other hand, release of pressure in either of the cylinders 28 will permit movement of the pulley 24 associated therewith 40 inwardly toward the respective cylinder 28, which movement will let out a proportionate length of the associated wire 22 to permit the respective boom 15 to be lowered. In the construction shown herein the length of piston rods 27 is such 50 that in folding the booms hydraulically they are moved only to an angle of slightly over 45° and then the remaining movement is by hand. It will be readily understood that the entire folding movement may be accomplished hydraulically 55 by the provision of a suitable system of pulleys in place of the pulleys 24.

A third cylinder 29 is shown herein mounted in a vertical position upon the upper transverse elements 11c of the pivotal rectangular frame. 60 This cylinder has a piston rod 30 extending upwardly therefrom, the upper end of which is suitably secured to the cross piece 12 and it will be readily understood that changes in pressure within the cylinder will cause vertical movement 65 of the rod 30, cross piece 12 and its appended parts, namely, struts 11, 10, and booms 14 and 15, relative to the rectangular frame and truck platform.

From the foregoing it will be seen that I have 70 provided a boom and boom supporting arrangement wherein height of the entire boom structure can be adjusted vertically by regulating pressure in the cylinder 29; wherein the side booms may be adjusted angularly with respect to the 75

ground by regulating pressure in cylinders 28; wherein the side booms may be folded into the supporting structure by pressure in cylinders 28, and wherein the folded booms, with the supporting structure may be folded from a working position over the end of the truck to a position above the truck to provide a compact unit suitable for road travel.

To the end that the contents of tank C may be agitated at all times, I have provided herein a pair of liquid pressure circuits. One is adapted to deliver liquid from the tank to the booms while the other operates simultaneously in parallel with said circuit to return liquid to the tank.

Referring now to Figs. 1 and 7, the supply tank C has pipes 31 and 32 extending longitudinally through the top and bottom respectively thereof. The pipe 31 has three series of holes therein, two series being directed toward the sides of the tank while another is directed downwardly. With such an outlet arrangement in the pipe 31 maximum agitation of the contents of the tank is obtained due to the flow of the incoming liquid down and across under the directing influence of the curved sides. This pipe constitutes the liquid inlet for the tank and is connected with conduit 33 to the circulating and agitating circuit of the pressure system to be described presently, while pipe 32 constitutes the outlet of the tank and is connected with a conduit 34 (herein designated as the main draw-off) to a liquid delivery circuit and to said circulating and agitating circuit of the pressure system.

The pumping arrangement shown in the present embodiment comprises a motor 35 which has a drive shaft 36 connecting with and driving a suitable high pressure pump 37. The shaft 36 has a drive pulley 38 mounted thereon which, through a belt 39 and a drive pulley 40, actuates a low pressure pump 41. The motor and pumps are suitably mounted on a truck platform shown herein by securing means such as angle bars 42.

The above mentioned circulating and liquid delivery circuits as heretofore explained, are adapted to operate in parallel under the influence of the pumps 37 and 41, the delivery circuit comprising conduits 51, 52 and 53 and the circulating circuit comprising conduits 58, 48, 46, and 47.

In order that tank C may be filled with liquid, the pump 41 is operated by motor 35 as above described and the inlet end (not shown) of a conduit 43 is connected with a suitable liquid reservoir. By manipulation of the handle of a two-way valve shown at 44, conduits 45 and 46 are placed in direct communication through valve 44. As the pump 41 operates, it draws liquid through conduits 43, 45, 46, and forces it out of a conduit 47 (which serves as the outlet of pump 41) into conduit 33 from whence it passes into the tank C through pipe 31. It is to be understood that if desired this filling operation may proceed during the function of the delivery circuit. When the filling operation is completed, the handle of valve 44 is reversed to place conduits 46 and 48 in communication, leaving conduits 43 and 45 entirely out of the liquid circuit.

The system is now in readiness for delivering liquid to the booms under the action of the high pressure pump 37, by which liquid is drawn from the tank through pipe 32, conduits 34, 49, and 50 (conduits 49 and 50 being designated the high pressure draw-off) and then ejected under high pressure into the delivery system which comprises conduits 51, 52, and 53. Liquid passing through

conduit 53 flows to the booms through a control system presently to be described. Connecting with this high pressure liquid delivery system (shown shaded in Fig. 7) are overflow conduits 54 and 55 and a relief valve 56 set, under normal conditions, at any convenient pressure. The intermittent overflow from conduits 54 and 55 occurring when the delivery pressure exceeds this point, passes into a conduit 57 and thence into the circulating and agitating system, (shown as unshaded conduits).

While the delivery circuit functions as above described, the agitating and circulating circuit is being independently operated by pump 41. This circuit comprises a low pressure draw-off 15 which includes conduits 58, 48, and 46, and return conduits 47 and 33, the latter connecting with pipe 31 in the tank C. It will be seen that when both pumps are effective and the valve 44 is manipulated to shut conduits 43 and 45 out of the system, the delivery circuit and the circulating circuit, as previously stated, operate in parallel. Thus while the delivery circuit is functioning to draw off liquid from the main draw-off conduit 34 for transmittal to the booms, the circulating circuit is also withdrawing liquid from conduit 34 to be returned to the tank C and, as previously stated, the effectiveness of the latter circuit for agitating the contents of the tank is not dependent upon excess pressure existing in the delivery circuit to create overflow.

To the end that the vertical position of the spray rig, the angle of the side booms 15 and the amount of liquid spray fed to the booms may be controlled, I provide the preferred control circuit shown in Figs. 3 and 6.

Referring to Fig. 3, a preferred control circuit is shown, mounted on the crosspiece 16d by brackets 16e, one of which is shown in Fig. 4, the crosspiece is in turn welded as at 16g to uprights 40 17 on the rear of the truck platform. The control circuit consists of an inlet conduit 59 which is connected by conduit 60 (Fig. 1) to the outlet 53 of the pressure system and extends upwardly, having a branch 61 extending therefrom. Liquid 45 under pressure created by pump 37 flows from branch 61 to the booms 14 and 15—15 through boom shut-off valves 62, 63, and 64 and conduits 65, 66 and 67 connected thereto, respectively. The feed of liquid under pressure, through the 50 conduit 59 and branch 61 and through the flexible conduits 65, 66 and 67 to the respective booms may be individually controlled by independent operation of shut-off valves 62, 63 or 64 or jointly by the operation of a master valve shown at 68. 55

Under normal operating conditions the high pressure delivery pump 37 operates at a constant rate, thereby creating constant liquid pressure in the delivery circuit, and since, under circumstances presently to be described, it is necessary 60 to control the volume of liquid discharged into the atmosphere through the booms, it is necessary to provide an overflow circuit for that portion of the liquid which periodically exceeds the requirements of the booms. This overflow circuit is shown herein as including that portion of conduit 59 which extends upwardly of the junction of the delivery branch 61, transverse conduit 69 having a pressure control valve 69a therein, and the downwardly and transversely extending return conduit 70. This return conduit in turn connects with a flexible pipe 71 (Fig. 1) which leads to an inlet 72 located at the bottom of tank C. Thus it will be seen that under the influence of the pump 37 liquid is forced through 75

the delivery system into the conduit 59 and thence through conduits 69, 70, and 71 back through the inlet 72 of the tank, and that by operation of the pressure control valve 69a, the pressure of the liquid in the entire delivery system and hydraulic system, to be described presently, will be regulated.

The amount of insecticide sprayed per area of field is a function of the pressure in the delivery system and the speed of the vehicle upon which the spray mechanism is being moved. To the end that a predetermined, uniform quantity of the insecticide may be sprayed over a given unit of field area and may be maintained uniform throughout unavoidable changes in speed of the vehicle, and in order that this uniformity may be maintained by an operator without interrupting the spraying operation, I have provided, and disclose herein, a preferred arrangement of indicating and manipulating mechanism. In the present embodiment this arrangement comprises a pressure gauge 73 which is responsive to pressure changes in the delivery system through a conduit 74 and which taps the delivery circuit through the conduit 59. A speedometer 73a which registers the speed of the vehicle, through suitable connections with a moving part of the vehicle (not here shown), is located adjacent the pressure gauge. The gauge 73 and speedometer 73a may be mounted in any suitable manner and in the present embodiment are shown secured by brackets 75 to the cross piece 16d.

Assuming that the vehicle is traveling over the plants to be sprayed at a given rate, and that the pressure gauge indicates a given pressure, which combination of speed and pressure results in the desired distribution of insecticide over the field, the operator merely observes the changes in vehicle speed in the speedometer and regulates the pressure in the delivery line proportionately by manipulating valve 69a, thereby maintaining constant the quantity of liquid distributed per unit area of field.

As previously described, the entire boom structure may be shifted vertically by creating pressure changes in a cylinder 29, and side booms 15 may be adjusted vertically by creating pressure changes in cylinders 28. Means is provided herein for creating these pressure changes in the cylinders by utilizing the normal pressure existing in the liquid delivery circuit. As shown herein, a pressure by-pass system 78 extends from the top of conduit 59 to the top of conduit 70. A bank of three two-way valves 79, 80 and 81 is mounted on this by-pass system 78, each valve having an operating lever 79a, 80a, and 81a respectively. Connecting with the valves are flexible conduits 82, 83 and 84 respectively.

The conduits 82 and 84 have their ends remote from the valves 79 and 81 connected to the outer end of each of the cylinders 28, while the conduit 83 is similarly connected with the bottom of the cylinder 29. During the operation of the pump 37 the pressure existing in the delivery circuit will of course exist likewise in the system 78. By manipulation of the handles of the two-way valves 79, 80 or 81, conduit 59 is placed in communication with conduits 82, 83 and 84 through 79b, 80b and 81b and valves 79, 80 and 81. Under these circumstances pressure in the liquid delivery system is transmitted to cylinders 28-28 and 29, thereby raising the rig and booms. When the rig and booms have been raised to the desired position by the above manipulation of

the valves, the handles of the latter are again moved to a neutral closed position to cut off communication between conduit 59 and the valves. When the handles are in this closed position, the conduits 82, 83 and 84 are also cut off from communication with the valves and the pressure then existing in the cylinders 28-28 and 29 is maintained to hold the rig and booms in the desired position. Should the operator now desire to move the rig or booms down, he again manipulates the valve handles into a third position. In this position communication between pressure conduit 59 and the valves is still cut off but communication has been established between the conduits 82, 83 and 84 and liquid return conduits 15 71c, 80c and 81c. Under these conditions the accumulated pressure in the cylinders is released by the return flow of liquid from the cylinders through conduits 82, 83 and 84, the valves, return conduits 79c, 80c and 81c, return conduit 78a, 20 conduits 70 and 71 to pipe 72 in tank C. It will be understood that this release of liquid permits the rig and boom to fall by gravity until the operator again moves the valve handles to either the neutral "cut off" position or the first described "raise" position. It will be further understood that the rig and booms may be regulated independently by independent movement of the valve handles 79a, 80a or 81a.

Briefly the operation of my spray mechanism is as follows: Assuming the spray rig to be in the position shown in Fig. 1, that is in its folded position in readiness for road travel, the anchor rod 16c is disconnected and the boom structure is then swung into a position shown in Figs. 3 and 4 about the pivot 16b. The operator then manipulates the valve levers 79a, 80a and 81a into a position to establish communication between the cylinders and conduits 79c, 80c and 81c and the booms 15 along with the boom supporting structure, which includes struts 10, 11, 13 and cross piece 12, assume the position shown in full lines in Fig. 2.

It is to be particularly noted at this point that I have provided herein a novel priming arrangement which comprises a conduit 41a which taps the conduit 54 of the high pressure system and injects liquid under the high pressure of the latter system into the conduit 46 of the low pressure system which serves as the inlet for the pump 41. A section 41b of the conduit 41a extends into and longitudinally of the conduit 46. The control of the flow of liquid from the conduit 54 to the conduit 46 through conduit 41a is obtained by manipulation of a suitable valve 41c. In effect liquid is conducted by the conduit 41a at high pressures from the conduit 54 into and longitudinally of the conduit 46 and in the direction of the low pressure pump 41. Under these conditions priming liquid for the pump 41 is drawn from the tank through conduits 34, 58, 48, and 46 in sufficient quantities to prime the pump 41 during the starting of the pressure system.

To start the mechanism it is first necessary for the operator to transfer a small quantity of solution, about a bucket full, into the bottom of the tank. The motor 35 is then started, whereby operation of the pumps 37 and 41 takes place. At this time the valve 41c is manipulated to bring the conduit 41a into operation whereby pressure developed by the pump 37 causes the injector-priming operation to take place. The operator then manipulates the lever 44 to connect conduits 43 and 45 with the conduit 46 of the pump 75

41. This pump now having been primed proceeds to withdraw solution from the main reservoir through conduits 43, 45 and 46 and conduct it to the tank through outlet conduits 47 and 33. 5
 5 This particular pumping operation is continued until the tank on the truck has been filled with solution, at which time the lever 44 is manipulated to disconnect conduits 43 and 45 and bring conduits 34, 58, and 48 into operation. The operator, who is stationed on the truck platform at the various controls hereinbefore described, has closed valve 68 to shut off the booms during the filling operation and has opened the valve 69a located in the transverse conduit 69, where- 10
 15 by pressure created in the delivery circuit by the pump 37 forces the liquid down through the return conduit 70 and into tank C through inlet 12 rather than through the branch 61 and into the booms. The filling operation having been completed, the operator then opens the valves 68 and 69a and the liquid delivery circuit now becomes effective to deliver insecticide to the booms. It will be readily understood that the pressure available to deliver insecticide into the 20 atmosphere through the booms may be controlled by the valve 69a, and in order that the priming operation be effective this valve must be at least partially closed until that operation is completed. 25

As previously explained, the high pressure delivery circuit connected with the pump 37 and the low pressure circulating circuit connected with the pump 41 are adapted to operate simultaneously, whereby the contents of tank C are continuously circulated and agitated throughout the operation of the spray mechanism.

Assuming that the operator has determined the proper readings on the pressure gauge 73 and speedometer 73a which will give a predetermined quantity of liquid to be distributed per unit of field area, he then watches the dials and regulates the valve 69a in accordance with the variations in the reading on the speedometer 73a.

Should variations in the contour of the land being sprayed occur, the booms 15 may be independently hydraulically regulated through cylinders 28-28 to compensate for these variations by manipulation of the valve levers 79 and 81. In the event that wind conditions or varying height of the plant require the height of the 40 boom structure to be regulated, this may also be accomplished hydraulically by actuation of cylinders through the valve lever 80. After a field has been sprayed and it is desired to transport the apparatus to a different territory, the entire 45 boom structure may be raised by the previously explained manipulation of the valve 80, and the side booms 15 may be drawn into their folded position by the wires 22 through the previously described manipulation of the valve levers 79 and 81 preparatory to the folding of the entire boom structure over the end of the truck into a position shown in Fig. 1.

Having thus described my invention, what I desire to secure by United States Letters Patent is:

1. In a spray machine, spraying mechanism, a platform for mounting said spraying mechanism, said spraying mechanism including a frame having upright elements, a standard on said platform for supporting said frame by pivotal engagement with said upright elements whereby said frame and its appended parts may be pivotally moved on said standard to be folded over said platform, a boom structure mounted on said frame to move vertically thereof in its entirety,

booms in said boom structure mounted to extend beyond the confines thereof and having pivotal attachment with said structure at their inner ends, a liquid supply for said spraying mechanism, a pressure system for transmitting liquid under pressure from said supply to said spraying mechanism, independent hydraulic motors each having a driven member, each of said members being operatively connected respectively with each of said pivoted booms and with the 10 vertically movable boom structure to adjust the position of said booms upon operation of the respective motor, an operating valve for each of said motors, pressure conduits from each of said motors to said pressure system. 15

2. In a spray machine, spraying mechanism, a platform for mounting said spraying mechanism, said spraying mechanism including a boom structure, means on said platform for supporting said boom structure for vertical movement with respect to said platform, said boom structure including booms mounted to extend beyond the confines thereof and having pivotal attachment with said structure at their inner ends, a liquid supply for said spraying mechanism, a pressure system for transmitting liquid under pressure from said supply to said spraying mechanism, independent hydraulically operating means connected with said pivoted booms and with the vertically movable boom structure, operating valves 20 for said hydraulically operating means, pressure conduits from said valves to said pressure system. 25

3. In a spray machine, spraying mechanism, means for mounting said mechanism, said mechanism including a boom structure supported by said mounting means, said structure being movable in its entirety with respect to said mounting means, a liquid supply for said spraying mechanism, a pressure system for transmitting liquid under pressure from said supply to said spraying mechanism, a hydraulic motor for said boom structure, a pressure actuated element in said motor, said element being operatively connected with said boom structure for moving the same 40 upon operation of the motor, an operating valve for said motor, a pressure conduit from said motor to said pressure system. 45

4. In a spray machine, spraying mechanism, means for mounting said mechanism, said mechanism including a plurality of spray distributing booms carried by said mounting means and secured thereto by pivotal means at adjacent ends of the boom, a liquid supply for said booms, a pressure system for transmitting liquid under pressure from said supply to said booms, independent hydraulic motors associated with each of said booms, pressure actuated elements in said motors, means for operatively connecting each element with a boom for moving the same pivotally upon operation of the respective motor, pressure conduits from said motors to said system and valves in said conduits for controlling the pressure transmitted to said motors. 50

5. In a mobile liquid insecticide spraying unit, 65 a platform, an insecticide supply tank, a pressure system, a hydraulic control circuit and an insecticide dispensing system mounted on said platform, conduits connecting said supply tank and said pressure system, conduits connecting said 70 pressure system and said control circuit, and conduits connecting said control circuit and said dispensing system, said pressure system being adapted to withdraw insecticidal liquid from said tank and deliver it to said dispensing system 75

- through said control circuit under pressure, said dispensing system including a boom structure movable bodily with respect to said platform and booms pivotable on said boom structure, a bypass in said control circuit, a plurality of valves in said bypass, a hydraulic motor for said boom structure, a pressure actuated element in said motor, said element operatively connecting with said boom structure for moving the same upon 5 operation of the motor, a plurality of hydraulic motors, pressure actuated elements in said motors, means for operatively connecting each of said elements with a boom for moving the same pivotally upon operation of the respective motor conduits from said valves in said bypass to each of said respective motors, said last named conduits being adapted to transmit operating pressure in said control circuit to said hydraulic motors upon manipulation of the respective 10 valves.
6. In a liquid insecticide spraying unit, an insecticide supply tank, a liquid pressure system, a hydraulic control circuit and an insecticide dispensing system, conduits connecting said supply tank and said pressure system, conduits connecting said pressure system and said control circuit and conduits connecting said control circuit with said dispensing system, said pressure system being adapted to withdraw insecticidal liquid from 15 said tank and deliver it to said dispensing system through said control circuit under pressure, said dispensing system including pivotally mounted booms, valve means in said control circuit, means operated by hydraulic pressure and connected with said booms, said pressure operated means being operable to shift the position of said booms about the pivots thereof and pressure conduits between said valve means and said hydraulically operated means.
7. In a liquid insecticide spraying unit, an insecticide supply tank, a liquid pressure system, a hydraulic control circuit and an insecticide dispensing system, conduits connecting said supply tank and said pressure system, conduits connecting 20 said pressure system and said control circuit and conduits connecting said control circuit and said dispensing system, said pressure system being adapted to withdraw insecticidal liquid from said tank and deliver it to said dispensing system through said control circuit under pressure, said dispensing system including a boom structure movable in its entirety with respect to the spraying unit, valve means in said control circuit, a hydraulic motor for said boom structure, a pressure actuated element in said motor, said element 25 operatively connecting with said boom structure for moving the same upon operation of the motor, a conduit from said valve means to said motor.
8. In an insecticide spraying machine, a liquid insecticide supply, a liquid dispensing system comprising movable booms, a pressure system between said supply and said dispensing system for transmitting liquid under pressure from said 30 supply to said dispensing system, pressure responsive means operatively connected with said booms to move the latter upon pressure changes, and means for transmitting pressure in said pressure system to said pressure responsive means.
9. In a spray machine, a spray rig, a boom supporting structure, said boom supporting structure being movably mounted on said spray rig for vertical movement relative thereto, means for moving said supporting structure through its vertical movement, said means including a hydraulic 35

motor mounted on said rig and having an actuating element operatively connecting with said structure, booms mounted on said structure for pivotal movement relative thereto, means for moving booms through their pivotal movement, 5 said means including, hydraulic motors mounted on said structure and means for operatively connecting said actuating elements with said booms.

10. In a mobile insecticide applicator, a vehicle, a rig mounted on the vehicle, said rig including a 10 rectangular frame mounted for pivotal movement about one end of the vehicle, the horizontal elements of said frame comprising slideways, a boom supporting structure carried by said frame, said structure including vertical elements 15 adapted to cooperate with said slideways, said structure being adapted to be moved vertically with respect to said vehicle and said frame, booms on said structure, said booms being pivotally secured thereto, being extensible beyond 20 the confines thereof to cover a wide area of the field to be sprayed during movement of the vehicle, and being foldable into the confines of said structure about said pivots.

11. In a mobile insecticide applicator, a vehicle, a rig mounted on the vehicle, said rig including a boom supporting structure mounted for pivotal movement about the end of the vehicle, said supporting structure including uprights secured to said vehicle for vertical movement relative thereto, booms carried by said structure and having pivotal connection therewith, said booms being extensible beyond the confines of said structure and being foldable into the confines of said structure about the pivots. 25

12. In a spray machine, a boom supporting structure, booms mounted on said structure by universal joints at their inner ends, elevating cables secured to said booms and extending upwardly thereof, means for withdrawing and letting out said cables to control the vertical, angular position of the booms, said booms being mounted to swing freely rearwardly about said universal joints. 40

13. In a spray machine, a boom supporting structure, booms mounted on said structure by universal joints, means for supporting said booms in an extended position outwardly from said structure and means for securing said booms against forward horizontal movement about said 45 universal joints. 50

14. In a spray machine, a boom supporting structure, booms mounted on said structure by universal joints, elevating cables secured to said booms and extending upwardly and inwardly to 55 said boom structure, a guy wire for each said boom having one end secured to the adjacent boom, extending rearwardly and having its other end secured to said structure to restrict forward movement of said boom about said universal 60 joints.

15. In a spray machine having a liquid supply, boom supporting means, booms movably mounted on said supporting means for movement from an extended, operative position to a folded 65 position, conduits connecting said liquid supply with said booms, means for propelling liquid under pressure from said supply to said booms and hydraulic motors associated with said booms, said motors having actuating elements, means for operatively connecting said elements with said booms to move the same from an extended to a folded position upon operation of the respective motor, the combination of a control circuit interposed in said conduits, said control circuit hav- 70 75

ing pressure conduits connecting said motors therewith, valves associated with said circuit for controlling the pressure in said pressure conduits and pressure indicating means operably connected with said control circuit and located in the vicinity of said valves.

16. In a mobile spray machine having a liquid supply, boom supporting means, booms movably mounted on said supporting means for movement from an extended, operative position to a folded position, conduits connecting said liquid supply with said booms, means for propelling liquid under pressure from said supply to said booms and hydraulic motors associated with said booms, said motors having actuating elements, means for operatively connecting said elements with said booms to move the same from an extended to a folded position upon operation of the respective motor, the combination of a single control circuit interposed in said conduits having pressure conduits connecting said motors therewith, valves in said circuit for controlling the pressure in said pressure conduits, another valve in said circuit for controlling the flow from said supply to said booms, pressure indicating means operably connected with said control circuit and located in the vicinity of said last named

valves and speed indicating means mounted in the vicinity of said first named valve.

17. In a spray machine, a boom supporting structure, uprights, a cross piece at the top of said uprights, said uprights having boom securing means at the lower ends thereof, booms so pivotally secured to said boom securing means that they may be moved vertically, power actuated operating elements mounted on said cross piece, and means connecting said operating elements and said booms for adjusting the angular position of said booms about the pivots upon actuation of said operating elements.

18. In a spray machine, the combination of a boom supporting structure, booms on said structure, connections for securing said booms to said boom supporting structure, including a rearwardly operating hinge connection between the inner end of said boom and said supporting structure, and means for operatively securing said boom in a laterally extended position with respect to said machine to afford rearward horizontal, pivotal movement of said boom when the latter strikes obstructions as said machine moves forwardly thereby.

LLOYD E. PITNER.
